ELECTRICALLY LIGHTED LAMP

Filed April 26, 1943

Fig. 2.

Fig. 3.

INVENTOR.
BY Henry J. E. Metzger *Evelyn Dore'* Agt.

Patented Apr. 25, 1944

2,347,313

Electrically lighted lamp, and particularly to an electric table lamp, which may be of any approved design or material—preferably of wood or plastic material—and which has a base 2 at its lower end, carries an electric light fixture 3 at its top and is provided with a flattened portion 4 through which a screw 5 extends. Two broad, flat arms 6 and 7, of wood, plastic material or the like, are secured to the flattened portion 4 by means of the screw 5 and a wing nut 8. Electric light fixtures 9 are pivotally secured to the free end of each arm. I prefer to carry out this feature of my invention in the manner shown in the drawing, where it will be seen that flat parts 10 carrying the light fixtures 9 are secured to the arms by means of screws 11 and wing nuts 12; each screw 11 extends through the free end of an arm and through one of the parts 10.

Current controlling means, such as switches 14, can be arranged at any suitable place of the lamp, and current conductors (not shown) can be either attached to the rear side of the lamp or can pass through suitable channels (not shown) in the various parts of the lamp.

If the parts of the lamp are in the position shown in Figs. 1 and 3, the lamp forms a can-

dleabrum, and two of its sources of light (9) throw light toward the table or surface on which the lamp stands, whereas three sources of light (3 and 9) throw light upwards, normally toward the ceiling of a room from which the light will be reflected in a well known manner.

By changing the position of the arms 6 and 7 and of the flat parts 10, various symbolic forms can be attained, for instance the form of a V as shown in Fig. 2. The lamp shades of the electric light fixtures 3 and 9 can be of any approved ornamental design or color. To facilitate the moving of the arms 6 and 7, particularly for forming the letter V, I prefer to make the lamp shade of the fixture 3 in the form of an inverted cone, as in the instance shown, where it will be seen that the lamp shades of the other fixtures 9 and the form of the base 2 as well are made conical.

By changing the position of the arms 6 and 7 and of the flat parts 10, various symbolic forms can be attained, for instance the form of a V as shown in Fig. 2. The lamp shades of the electric light fixtures 3 and 9 can be of any approved ornamental design or color. To facilitate the moving of the arms 6 and 7, particularly for forming the letter V, I prefer to make the lamp shade of the fixture 3 in the form of an inverted cone, as in the instance shown, where it will be seen that the lamp shades of the other fixtures 9 and the form of the base 2 as well are made conical.

10 In order to emphasize the symbol formed by the arms 6 and 7, I prefer to paint the arms 6 and 7 in a dark color and have all other parts in lighter colors. For instance, if a lamp according to the present invention is offered for sale as, say, a "1943 good luck victory lamp," I paint the arms 6 and 7 dark red and keep all other parts in white; or I make the arms dark red or dark blue and keep the lamp shades and the base blue, white and red.

20 25 30 35 40 45

In order to emphasize the symbol formed by the arms 6 and 7, I prefer to paint the arms 6 and 7 in a dark color and have all other parts in lighter colors. For instance, if a lamp according to the present invention is offered for sale as, say, a "1943 good luck victory lamp," I paint the arms 6 and 7 dark red and keep all other parts in white; or I make the arms dark red or dark blue and keep the lamp shades and the base blue, white and red.

The fixtures 9 can be adjusted in positions which are adapted to create attractive light effects and to improve the appearance of the symbol formed by the arms. Since the arms 6 and 7 are of considerable width, large washers 15 can be used to prevent any damaging of the arms when the screws 5 or 11 are firmly tightened. The adjustable parts can, therefore, be held safely in any desired position.

While there has been shown and described and pointed out the fundamental novel features of the invention as applied to one single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What I claim as my invention and desire to secure by Letters Patent in the United States is:

50 55 1. In an electric lamp, the combination of a conical base, an upright shaft fixed thereon and carrying conductors for electricity and having switches at its outer side, a flat vertical member extending from the upper end of said shaft, a

central electric light fixture having an inverted conical lamp shade secured to the upper end of said vertical member, flat arms pivotally connected to said vertical member by means of a screw and a wing nut, and flat parts being pivotally connected to said flat arms and carrying electric light fixtures, all substantially as set forth.

2. An electric lamp comprising a center post having a base plate at its lower end and a flat-

tened portion at its upper end; an electric light fixture carried by said flattened portion of said center post; two broad, flat arms pivotally connected to said flattened portion of the center post; flat parts, carrying electric light fixtures, pivotally secured to the free end of each of said arms; and means for retaining said arms and said flat parts at the free ends of said arms in any chosen position.
